UNITED STATES PATENT OFFICE.

WACLAW DZIMITOWICZ, OF PITTSBURGH, PENNSYLVANIA.

BABY-WALKER.

1,326,921.

Specification of Letters Patent

Patented Jan. 6, 1920.

Application filed January 30, 1919. Serial No. 274,060.

To all whom it may concern:

Be it known that I, WACLAW DZIMITOWICZ, a citizen of Poland, residing at Pittsburgh, in the county of Allegheny and State of Pennsylvania, have invented certain new and useful Improvements in Baby-Walkers, of which the following is a specification.

The primary object of the invention is the provision of a baby walker adapted to be compactly folded when not in use and readily set up for resiliently supporting a child in walking position, the device being adjustable for children of different heights.

A further object of the invention is to provide a spring seat for small children adjustable in height with respect to the floor upon which the device is adapted to travel, provision being made for readily folding the structure and retaining the same in its knock-down form when not desired for use.

A still further object of the invention is to provide a baby walker that possesses great strength and one that is compactly foldable for storage or shipping purposes and that is also easy and inexpensive to manufacture.

With these and other objects in view the invention will be hereinafter more fully described in connection with the accompanying drawings and in which like reference characters designate corresponding parts throughout the several views.

In the drawings,

Figure 1 is an elevational view of the invention set up for use,

Fig. 2 is a top plan view thereof,

Fig. 3 is a detail sectional view of one of the adjustable leg members employed,

Fig. 4 is a top plan view showing the hinge connection between the lower end of one of the leg members and a corner of the supporting frame with said leg member latched in its folded position,

Fig. 5 is a sectional view taken upon line V—V of Fig. 4,

Fig. 6 is a vertical sectional view showing the removable connection between the free end of one of the leg members and the table or railing of the device and

Fig. 7 is a bottom plan view of a portion of said railing showing the socket member of the leg connection.

The general form of my baby walker is one that is well known in the art, broadly consisting of a rectangular frame 10 having a table or railing 11 in the form of a ring

supported upon said frame by means of legs 12 while a seat board 13 for the child is resiliently suspended from the rail 11 by a plurality of helical springs 14. Suitable casters 15 are provided beneath the frame 10 for moving the device along the floor such as 16 and the board 13 is provided with substantially semi-circular cut-away portions 17 adapted to receive the legs of the child 18 therethrough when the child is seated upon said board with its body positioned upwardly through the ring 11, the latter being convenient for grasping as well as retaining the child upon said seat.

The legs 12 are made adjustable in length so as to position the seat board 13 at different distances from the frame 10 as well as above the floor 16 to accommodate children of different heights. These legs 12 are formed of two sections, the lower section 18 of each leg having a bolt 19 extending therethrough and through a longitudinal slot 20 of the upper leg section 21, whereby tightening of the wing-nut 22 of the bolt 19, the leg sections 18 and 21 are retained adjusted for providing a leg of the proper length desired.

A hinge 23 is diagonally secured adjacent each corner of the frame 10 having one leaf 24 of the hinge attached to the outer side of the adjacent lower leg section 18, whereby the leg may be elevated at an inclination with the frame 10 when the device is set up for use as shown in Fig. 1 or may assume a horizontal position within the frame 10 when the device is folded as shown in Fig. 5. A spring latch 25 is provided for each corner of the frame, upon which the bottom of the adjacent leg section 18 is adapted to rest when the device is set up, while the latches 25 overlie the leaves 24 of the springs 23 when the legs are in their folded positions.

Headed studs 26 are carried by the free ends of the leg sections 21 adapted for reception within the sockets 27 upon the lower face of the ring 11. The socket member 27 has a U-shaped portion 28 opening inwardly of the ring and with an inwardly struck resilient tongue or spring 29 for engaging the end of the stud 26 when forced to its seating position within the socket.

The complete operation of the device will be apparent from this detailed description thereof, the same being maintained set up for use by the legs 12 maintained open by

the spring latches 25 and connected with the ring 11 by the studs 26 and sockets 25. When it is desired to place the invention in its folded form, the studs 26 are forced 5 inwardly out of the sockets 27, the nuts 22 loosened and the upper leg section 21 lowered to the desired extent and upon swinging the latches 25 adjacent one side of the frame, the legs may be freely folded in- 10 wardly of the frame 10. The latches 25 will then be returned to their former positions but overlying the leg portions 18 so that the same will be prevented from opening until the latches 25 are again released.

15 A serviceable baby walker is provided capable of accommodating different sized children and being foldable for storing away when not desired for use.

What I claim as new is:—

20 1. A device of the class described comprising a rectangular frame, supporting legs, hinges connected between said legs and frame, retaining latches for the legs when folded and when unfolded pivoted at one of 25 their ends to the frame, a table ring, sockets upon the bottom of said ring, springs extending into said sockets, studs upon the free ends of said legs adapted for detachable connection with said sockets and 30 springs, and a seat board resiliently suspended from said ring.

2. A device of the class described comprising a ring, a seat board resiliently sus-

35 pended from said ring, sockets upon the bottom of the ring having U-shaped openings inwardly thereof, and provided with retaining spring portions, legs formed of upper and lower sections, studs upon the upper sections of said legs adapted for detachable connection with said sockets and 40 securing means between the sections of said legs whereby the ring and seat are maintained at adjusted elevations.

3. A device of the class described comprising a ring, a seat board resiliently suspended from said ring, sockets upon the bottom of the ring having U-shaped openings inwardly thereof, and provided with retaining spring portions, legs formed of upper and lower sections, studs upon the 45 upper sections of said legs adapted for detachable connection with said sockets, and securing means between the sections of said legs whereby the ring and seat are maintained at adjusted elevations, a supporting 50 frame, hinges connected between said frame and the lower sections of the legs, casters beneath said frame, and a latch for each hinge carried by the frame adapted for overlying said hinges when the legs are folded 55 within the frame, the said latches being supportingly positioned beneath the lower sections of the legs when the device is set up for use.

In testimony whereof I affix my signature. 60
WACLAW DZIMITOWICZ.
